DESIGN FOR A TRAY

Jean O. Reinecke and James F. Barnes, Chicago,
Ill., assignors to McGraw Electric Company,
Elgin, Ill., a corporation of Delaware

Application August 19, 1939, Serial No. 86,786

Term of patent 7 years

To all whom it may concern:

Be it known that we, Jean O. Reinecke and James F. Barnes, citizens of the United States, both residing at Chicago, in the county of Cook and State of Illinois, have invented a new, original, and ornamental Design for a Tray, of which the following is a specification, reference being had to the accompanying drawing, forming part thereof, in which

Fig. 1 is a top plan view of a tray embodying our new design;

Fig. 2 is an enlarged detail top plan view of the ornamentation at each end of the tray, the dominant feature of the new design residing in the portions shown in full lines; and

Fig. 3 is a side elevational view of the tray shown in Fig. 1.

We claim:

The ornamental design for a tray, substantially as shown and described.

JEAN O. REINECKE.
JAMES F. BARNES.
